UNITED STATES PATENT OFFICE.

LESTER A. WERNERY, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed October 21, 1921. Serial No. 509,225.

To all whom it may concern:

Be it known that I, LESTER A. WERNERY, a citizen of the United States, residing in Brooklyn Borough, in the county of Kings, 5 city and State of New York, have invented certain new and useful Improvements in Typewriting Machines, of which the following is a specification.

The present invention relates to an improved means in a typewriting machine, more particularly of the front-strike class, for displacing the platen with respect to the paper-guide, to permit of correct and easy insertion of considerable thicknesses of paper, or of paper with clasps and the like attached thereto; and also relates to an improved means for throwing the usual feed or pressure-rolls off the platen preliminary to insertion of the work-sheets.

An object of the invention is the provision of means whereby the platen may be displaced substantially vertically, and without appreciable rotary movement, from its normal to its sheet-inserting position; thus 25 maintaining the platen as a whole at all times in substantially the same position with respect to the operator, and thus causing the printing line of the platen, when the latter is in sheet-inserting position, to present itself in practically its true position at the central front part of the platen, so that the work-sheets may be set and adjusted with ease and certainty with respect to the printing line, as if the platen had not been displaced:—all as distinguished from those devices of the prior art in which the platen in the displacing operation has been thrown back from its normal position, and the printing line turned from the direct line of 40 vision of the operator.

Another object of the invention is the provision of means whereby in a single, or at least in a practically continuous, operation, the feed or pressure-rolls may be thrown off the platen, and the platen itself displaced to sheet-inserting position. Heretofore, the rolls have been thrown off by one lever or operation, and the platen displaced by an entirely different operation; 45 the operator being required to move his hand from one lever to another, and often being required to use both hands in effecting the two separate operations. By means of

the present invention the two operations may be effected quicker and with less trouble 55 than heretofore.

Other features and advantages will hereinafter appear.

In the accompanying drawings,

Figure 1 is a top plan view of a platen-carriage and assembled parts thereon embodying the features of the present invention.

Figure 2 is a perspective view, looking down from the left, showing certain of the parts at the right-hand end of the platen in their relation to the platen.

Figure 3 is a view in right-hand elevation, showing the normal or printing position of the parts.

Figure 4 is a view similar to Figure 3, except that the first step of the operation of moving the parts to sheet-inserting position has been effected; to wit, the throw-off of the feed or pressure-rolls.

Figure 5 is a view similar to Figures 3 and 4, except that the parts are all in sheet-inserting position.

Referring to the drawings, the platen 1 is shown as having bosses 2 at the ends thereof, fixed as by means of pins 3 to a platen-shaft 4. The platen-shaft 4, at either end, has bearing in, and is supported by, one arm 5 of an inverted V-shaped rocker, the other arm 6 of which rocker is pivoted at 7 to the platen-frame 8; so that, as hereinafter pointed out, the platen may have an up-and-down movement around the pivot 7 on an effective radius or arm which is the straight line between the pivot 7 and the axis 4 of the platen.

Coaxially mounted on the platen-frame 8, to turn therein, one on either side of the frame, are stub-shafts 9, each having secured thereto a hand-wheel 10 for rotating the same. In normal or printing position of the platen, the shafts 9 are coaxial with the platen-shaft 4. Fast to the left-hand shaft 9 is a line-space ratchet-wheel 11, adapted to be engaged and turned by a pawl 12 on a slide 13, which has reciprocatory movement on the platen-frame; being held in and returned to normal position by a spring (not shown), and being thrown rearward in the line-spacing operation by a bell-crank 105 hand-lever 14, pivoted at 15 to the platen-

frame, and adapted to engage an offset 16 on the slide 13; all of which line-feed mechanism is of the well-known Underwood type-writer structure.

- 5 For line-feeding the platen from the above-described line-space mechanism, whether the platen be in normal or sheet-inserting position, the following mechanism is employed. Fast to each of the shafts 9 is a pinion 17.
10 Bosses 18, on which the pinions 17 are carried, are secured to the shafts 9 by means of pins 19. Loose on each of the rocker pivot-pins 7 are two small pinions 20 and 21. Each pair of pinions 20 and 21 is fast on a sleeve 22 loose on the pins 7, so that the pinions 20 and 21 turn as a unit. The arm 6 of the corresponding rocker lies between the pinions 20 and 21, and has direct bearing on the sleeve 22. The pins 7 are shown
15 as threaded, as at 23, into bosses 24 on the platen-carriage. Each of the pinions 17 on the shafts 9 meshes with one of the pinions 20 on the pins or stub-shafts 7. On bosses 25, pinned as at 26 to the platen-shaft
20 4, are pinions 27, one at each end of the platen-shaft. Each of the pinions 27 meshes with one of the pinions 21 on the pins or stub-shafts 7.

With the parts in normal position, line-spacing is effected by operation of the line-space lever 14 in the usual manner. The line-space ratchet-wheel 11, however, instead of turning the platen directly, as if fast to the platen-shaft 4, turns the left-hand stub-shaft 9, causing the left-hand pinion 17 to be rotated; and, through the medium of the smaller pinions 20 and 21, driving the left-hand pinion 27, which is fast to the platen-shaft, thereby causing the platen to be turned according to the extent of movement of the line-space ratchet-wheel 11. Since the right-hand gear 27 is fast to the platen-shaft, the right-hand gears 20, 21 and 17 receive a corresponding line-space movement.

When the parts are thrown to sheet-inserting position, not only are the front pressure-rolls 28 and rear pressure-rolls 29 thrown to inoperative position, but the platen is itself lifted from its Figure 3 to its Figure 5 position, to provide ample space between the platen and the paper-shelf 30 for the insertion of any desired thickness of sheets, fasteners and the like. The pressure-rolls 28 and 29 are thrown off in the manner common to Underwood typewriting machines: that is to say, these rolls are carried by the arms 31 and 32, respectively, of bell-cranks which are pivoted on a shaft 33 below the platen. Set between the other arms 34 and 35 of these bell-cranks is a rotary shaft 36, having flats against which the arms 34 and 35 rest when the rolls are in normal position (see Figure 3), but which are turned from Figure 3 to Figure 4 position to spread

the arms 34 and 35, thereby rocking down the arms 31 and 32 to throw off the rolls when the shaft 36 is turned by an arm 37 thereon, operated by a link 38. The link 38 connects to, and is ordinarily operated by, an arm 39 upon a shaft 40, in turn operated by a finger-piece or arm 40* also on the shaft 40. 70

In the present invention, the arm 39 on the shaft 40 is actuated, for the throw-off operation, by means of a lever 41, one end of which is slotted at 42 to engage the pin 44, by means of which the link 38 is connected to the arm 39. The other end of the lever 41 carries a finger-piece 45 for operating the same. The lever 41, near the centre thereof, has a boss 46, through which passes a screw 47 (see Figure 1), to fix the same to the reduced right-hand end of a shaft 48, which is supported by, and is adapted to turn in, bearings in the rockers 5—6. The lever 41 is therefore, in effect, pivoted at 48, so that a downward, rearward thrust upon the handle 45 will move the parts from Figure 3 to Figure 4 position, this movement being limited by the pin 44 on the arm 39 engaging the rear end of the slot 42, as shown in Figure 4. The lever 41 in moving from Figure 3 to Figure 4 position causes the arm 39 to be lifted, as indicated, to throw off the pressure-rolls 28 and 29, in the usual manner. The movement of the lever 38 thus far is a pivotal movement.

Fast to the right-hand platen-frame-member is a hook-shaped device 49, the hook of which is formed by an arcuate slot 50, adapted to receive a pin 51 on the lever 41; and in which slot 50 the pin 51 travels from Figure 3 to Figure 4 position. Until the pin 51 is clear of the slot 50, no rearward or translatory movement of the lever 41 is permissible. When the pin 51 is once clear of the slot 50, however, the lever 41 may be thrust rearward as a unit from Figure 4 to Figure 5 position; because the rocker 5-6, on which the lever 41 is carried, is itself pivotally mounted on the platen-frame at 7. On arrival of the parts in the Figure 4 position, therefore, a rearward bodily thrust of the lever 41 may be effected, causing the member 5-6 to be rocked around its axis 7; and, in so rocking, to lift the platen from Figure 4 to Figure 5 position. During this lifting of the platen, the pinions 20 remain in mesh with the pinions 17, and the pinions 21 in mesh with the pinions 27; the rockers 5-6 being free to turn independently of the sleeves 22, on which the pinions 20 and 21 are mounted, and the platen itself and the pinions 27, which are fast thereto, also being free to turn with the platen-shaft 4. On arrival, therefore, of the parts in Figure 5 position, the line-spacing connections to the line-space ratchet-wheel 11 are the same as before; and, upon operation of the line-space

lever 14 in sheet-inserting position, the platen will be given any desired line-space-feed.

As before noted, the true arm, upon which the platen is lifted, is defined by a substantially horizontal line intersecting the axis 4 of the platen and the axis 7 around which the rockers 5—6 turn. In the Figures 3 and 4 position of this arm 4—7, it is shown as inclined at a slight angle forwardly and downwardly to the horizontal, whereas, in the Figure 5 position, it is shown as inclined slightly upwardly and forwardly. In the mean of the upper and lower positions of the arm 4—7, it is horizontal. The movement of the platen is substantially a vertical movement. As shown in the drawings, the axis of the platen falls in the same vertical plane in the upper and lower positions of the platen; and, in the mean position of the latter, is only one sixty-fourth of an inch forward of that plane. In fact, the movement of the platen is so nearly vertical, as the parts are shown in the drawings, that the rotation of the platen in moving from one position to the other, caused by the intermeshment of the gears 27 with the gears 21, is not of any consequence to the operator. The printing line is thus maintained at all times in substantially its correct position at the front centre of the platen.

Variations may be resorted to within the scope of the invention, and portions of the improvements may be used without others. Having thus described my invention, I claim:

1. In a typewriting machine, the combination of a platen-frame, a paper-guide on said frame, a rotary platen displaceable up and down in said frame with respect to the paper-guide between a printing position and a non-printing sheet-inserting position, means arranged to effect such platen-displacement in any rotative position of the platen without substantially rotating the platen, line-spacing mechanism including a non-displaceable ratchet-wheel, and means operatively connecting said ratchet-wheel and the platen in all positions of the platen.

2. In a typewriting machine, the combination of a platen-frame, a rotary platen displaceable up and down in said frame, a paper-guide on said frame extending downwardly and forwardly to the rear of the platen, and thence partway around the platen, in conformity thereto to the front thereof, means for limiting the extent of the platen-displacing movement to arrest the platen always in a uniform position with the line of writing in view of the operator, and platen-displacing means controlling the platen to move substantially along the bisector of the arc of the portion of the paper-guide that conforms to the platen, to separate the platen from the paper-guide to a

substantial extent at both the front and rear in said limited movement to permit a thick work-pack to be inserted between the platen and the paper-guide.

3. In a typewriting machine, the combination of a platen-frame, a rotary platen movable up and down in said frame, a paper-guide on the frame extending downwardly and forwardly to the rear of the platen and thence partway around the platen, in conformity thereto, to the front thereof, and a platen-displacing carrier in which the axis of the platen is mounted, said carrier being pivoted to the platen-frame substantially horizontally to the rear of the platen-axis, the arrangement being such that the platen is displaced substantially along the bisector of the arcuate portion of the paper-guide when moved by the carrier and thereby separated substantially equally from the paper-guide at the front and rear for sheet-insertion.

4. In a typewriting machine, the combination of a platen-frame, a rotary platen, a paper-guide on the frame, platen-displacing means for separating the platen from the paper-guide comprising a handle, and locking means for normally retaining the platen in writing position, said handle being movable in one direction to unlock the platen and in another direction to displace the platen.

5. In a typewriting machine, the combination of a platen-frame, a paper-guide on said frame, a rotary platen movable up and down in its frame with respect to the paper-guide to cause the axis of the platen to be displaced between two positions in a vertical plane, one of which positions is the normal or printing position of the platen and the other of which positions is a sheet-inserting position, means for effecting such displacement of the platen, and line-spacing mechanism in operative connection with the platen in both positions of the latter, said line-spacing mechanism comprising a shaft in fixed position on the platen-frame, a ratchet-wheel and a gear on said shaft, a gear fast to the platen, and gearing from said gear on the line-space shaft to said gear on the platen.

6. In a typewriting machine, the combination of a platen-frame, a paper-guide on said frame, a rotary platen movable up and down in its frame with respect to the paper-guide to cause the axis of the platen to be displaced between two positions in a vertical plane, one of which positions is the normal or printing position of the platen and the other of which positions is a sheet-inserting position, a carrier for the platen pivoted at the rear thereof to the platen-frame, means for rocking the carrier to effect such displacement of the platen, and line-spacing mechanism in operative connection with the

platens in both positions of the latter, said line-spacing mechanism comprising a shaft in fixed position on the platen-frame, a ratchet-wheel and gear on said shaft, a gear fast to the platen, and gearing on the axis of the carrier connecting the gear on the line-space shaft to the gear on the platen.

7. In a typewriting machine, the combination of a platen-frame, a rotary platen, feed-rolls and a paper-guide on said frame, means for throwing the feed-rolls off the platen, means for displacing the platen from the paper-guide, and a device connected to both the feed-roll throw-off means and the platen-displacing means for operating the same, said last-mentioned device having a pivotal movement to throw off the feed-rolls and another movement to displace the platen.

8. In a typewriting machine, the combination of a platen-frame, a rotary platen, feed-rolls and a paper-guide on said frame, means for throwing the feed-rolls off the platen, means for displacing the platen from the paper-guide, and a device connected to both the feed-roll throw-off means and the platen-displacing means for operating the same, said last-mentioned device having a pivotal movement to throw off the feed-rolls and a subsequent translatory movement to displace the platen.

9. In a typewriting machine, the combination of a platen-frame, a rotary platen, feed-rolls and a paper-guide on said frame, means for throwing the feed-rolls off the platen, means for displacing the platen from the paper-guide, a device connected to both the feed-roll throw-off means and the platen-displacing means for operating the same, said last-mentioned device having a pivotal movement to throw off the feed-rolls and a subsequent translatory movement to displace the platen, and a lock for preventing the translatory movement of said device until its aforesaid pivotal movement has been effected.

10. In a typewriting machine, the combination of a platen-frame, a rotary platen, feed-rolls and a paper-guide on said frame, means for throwing the feed-rolls off the platen, means for displacing the platen from the paper-guide, a common operating lever connected to the feed-roll throw-off means and to the platen-displacing means, and means to mechanically control the order of operation of the feed-roll throw-off means and the platen-displacing means by the lever.

11. In a typewriting machine, the combination of a platen-frame, a rotary platen, feed-rolls and a paper-guide on said frame, means for throwing the feed-rolls off the platen, means for displacing the platen from the paper-guide, a handle for operating the feed-roll throw-off means and the platen-displacing means, and a cam controlling the operation of said handle to compel the platen

to remain in normal position until the feed-roll throw-off movement has been completed.

12. In a typewriting machine, the combination of a platen-frame, a rotary platen, feed-rolls and a paper-guide on said frame, means for throwing the feed-rolls off the platen, means for displacing the platen from the paper-guide, and means for controlling the operation of said feed-roll throw-off means and said platen-displacing means, arranged to prevent the displacing of the platen prior to the throw off of the feed-rolls and also to prevent the return of the feed-rolls to normal position while the platen is in a displaced position.

13. In a typewriting machine, the combination of a platen-frame, a rotary platen, feed-rolls and a paper-guide on said frame, means for throwing the feed-rolls off the platen, means for displacing the platen from the paper-guide, a lever to which said feed-roll throw-off means and said platen-displacing means are connected, said lever having a pivotal movement to throw off the feed-rolls and a translatory movement to displace the platen, a tooth on said lever, and a stop co-operating with said tooth to prevent translatory movement of the lever until the pivotal movement thereof shall have caused the tooth to clear the stop.

14. In a typewriting machine, the combination of a platen-frame, feed-rolls, a paper-guide and a rocker in said frame, a platen on said rocker to be displaced thereby between a normal position and a sheet-inserting position, a lever pivoted to said rocker, and means connected to said lever with provision for lost motion for throwing the feed-rolls off the platen; whereby, when said lever is swung on its pivot, the feed-rolls are thrown off, and, when the lever is given a translatory movement, said rocker is actuated to displace the platen.

15. In a typewriting machine, the combination of a platen-frame, feed-rolls, a paper-guide and a rocker on said frame, a platen on said rocker to be displaced thereby between a normal position and a sheet-inserting position, a lever pivoted to said rocker, means connected to said lever with provision for lost motion for throwing the feed-rolls off the platen; whereby, when said lever is swung on its pivot, the feed-rolls are thrown off, and, when the lever is given a translatory movement, said rocker is actuated to displace the platen, and line-spacing mechanism for the platen in operative connection therewith in both normal and sheet-inserting positions thereof, said line-spacing mechanism comprising a line-space shaft in fixed position on the platen-frame, a line-space ratchet and gear on said shaft, a gear fast to the platen, and gears on the pivot of said rocker connecting the gear on the line-space shaft with the gear on the platen.

16. In a typewriting machine, a platen-frame, a platen displaceable in said frame, platen-displacing means, feed-rolls co-operating with the platen, means for throwing off the feed-rolls, a handle pivoted on the platen-displacing means, and a lost-motion connection between the handle and the feed-roll throw-off means, said handle being movable at first relatively to the platen-displacing means to throw off the feed-rolls and then relatively to the feed-roll-throw-off means by reason of the lost-motion connection to displace the platen, said lost-motion connection limiting the movement of the platen-displacing means and thereby determining the displaced position of the platen. 15
